DESK SET

Dorothy Harcourt Turner, Atlanta, Ga., assignor to Scripto, Inc., a corporation of Georgia

Application October 30, 1956, Serial No. 43,596

Term of patent 14 years

(Cl. D74—1)

Fig. 1 is a front perspective view of a desk set, showing my new design;

Fig. 2 is a top plan view thereof;

Fig. 3 is a side elevational view thereof; and

Fig. 4 is a bottom plan view thereof.

I claim:

The ornamental design for a desk set, as shown.
